US00D808639S

(12) **United States Design Patent** (10) **Patent No.:** **US D808,639 S**
(45) **Date of Patent:** **** Jan. 30, 2018**

(54) **SYSTEMS AND METHODS FOR AN INFANT STABILIZATION DEVICE**

(71) Applicant: **Infant Guard LLC**, Austin, TX (US)

(72) Inventor: **Andrew R. Gillam**, Austin, TX (US)

(73) Assignee: **Infant Guard LLC**, Austin, TX (US)

(**) Term: **15 Years**

(21) Appl. No.: **29/537,269**

(22) Filed: **Aug. 24, 2015**

Related U.S. Application Data

(63) Continuation of application No. 14/481,597, filed on Sep. 9, 2014, now Pat. No. 9,144,322.

(51) **LOC (11) Cl.** **03-99**

(52) **U.S. Cl.** **D3/213**

(57) **CLAIM**

The ornamental design for a systems and methods for an infant stabilization device, as shown and described.

DESCRIPTION

FIG. 1 is perspective view of a systems and methods for an infant stabilization device showing our new design thereof; FIG. 2 is a front view of the systems and methods for an infant stabilization device showing our new design in use; FIG. 3 is a rear view of a portion of the systems and methods for an infant stabilization device, shown separately from the second portion for ease of disclosure; FIG. 4 is a front view thereof; FIG. 5 is a left side vide thereof; FIG. 6 is a right side vide thereof; FIG. 7 is a top view thereof; FIG. 8 is a bottom view thereof; FIG. 9 is a front view of the second portion of the systems and methods for an infant stabilization device, shown separately from the first portion for ease of disclosure and in an alternate state; FIG. 10 is another front view of the second portion of the systems and methods for an infant stabilization device, shown separately from the first portion for ease of disclosure and laid flat; and, FIG. 11 is a rear view thereof.

The broken lines depict environment that forms no part of the claimed design.

1 Claim, 11 Drawing Sheets
